DESIGN FOR A CAGE

Peter P. Benson, Detroit, Mich.

Application January 6, 1934, Serial No. 50,342

Term of patent 7 years

To all whom it may concern:

Be it known that I, PETER P. BENSON, a citizen of Poland, residing at Detroit, in the county of Wayne and State of Michigan, have invented a new, original, and ornamental Design for Cage, of which the following is a specification, reference being had to the accompanying drawing, forming part thereof.

The figure is a front elevation of a cage showing my new design.

I claim:

The ornamental design for a cage, as shown.

PETER P. BENSON.
